GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

HINGE JOINT.

1,422,048.

Specification of Letters Patent.

Patented July 4, 1922.

Application filed December 6, 1921. Serial No. 520,242.

To all whom it may concern:

Be it known that I, GILBERT W. GOODRIDGE, a citizen of the United States of America, residing at Bridgeport, in the county of Fairfield and State of Connecticut, have invented certain new and useful Improvements in Hinge Joints, of which the following is a specification.

My invention relates to hinge joints, and especially to hinge joints in face plates for electrical fittings. The object of my invention is to provide, first, a hinge joint lying in the plane of the face plate; second, to form the joint elements entirely from the metal of the plate. While these objects may be accomplished in various ways, a single specific embodiment thereof is illustrated in the accompanying drawings, in which—

Fig. 1 is a plan view of the face plate of a flush receptacle in which my invention is embodied in one form;

Fig. 2 is a longitudinal central section therethrough;

Fig. 3 is a plan view of a plate from which the door has been blanked;

Fig. 4 is a similar view showing the door in position ready for completion of the hinge joint;

Figs. 5, 6 and 7 are, respectively, sections on the lines 5—5, Fig. 3; 6—6, Fig. 4 and 7—7, Fig. 1; and

Fig. 8 is a plan view of the door blanked from the plate shown in Fig. 3.

While the present form of joint may be used to advantage in various structures, I have illustrated it in connection with a face plate for a flush receptacle of a type well known in electrical-wiring devices. Inasmuch as the invention relates to the door hinge in the face plate, the receptacle proper has not been illustrated, but it will be understood that the face plate 10 is of the type commonly employed to overlie a receptacle, not only to impart a finish to the installation, but to protect the equipment against the entry of dust, etc. The face plate is pierced by an opening 11 normally closed by the door 12 as usual, and held in position by securing screws passing through the countersunk holes 13 at opposite ends of the face plate. The door 12 is ordinarily supported on the face plate by a hinge effected by hinge pins secured on the inner face of the door, and swivelling in sockets secured to the inner face

of the plate. The hinge joint is therefore not in the plane of the plate, but below the latter. Inasmuch as the joint is commonly arranged at one end of the door opening, the door impinges against the adjacent edge of the latter, and when open is stopped in a position slightly past that at right angles to the plane of the plate. This renders the insertion of a plug into the receptacle more or less inconvenient, since the fingers are apt to be impeded by the open door as the plug is rotated to screw into the receptacle. Moreover, the hinge parts must be secured not only to the butt of the door, but also to the plate by means of rivets, or the like, which may be of a metal slightly differing in color from that of the door and face plate, and thus mar the appearance of the plate.

According to the present invention, the hinge is located directly in the plane of the plate, so that the door swings open much further than is ordinarily possible in standard constructions. The elements which constitute the joint are formed of the metal of the plate itself, thus insuring uniformity of color at all points. The construction furthermore eliminates certain forming operations and additional metal parts which have hitherto added to the expense of manufacture.

In the particular form here shown the door 12 (Fig. 8) is blanked from the plate 10 by suitable punch die. It is provided at one end with a hinge butt 14 from the opposite edges of which project hinge lugs 15. As struck from the plate these lugs are rectangular. Before the hinge joint is completed, however, the lugs are subjected to a suitable forming operation to round their corners until the lugs present a substantially circular cross section, as illustrated in Figs. 6 and 7.

Following the removal of the door 12 from the plate 10, the latter is subjected to the action of suitable dies to form the portion of the plate on opposite sides of the slots 16 from which the hinge lugs 15 have been punched, into outstanding wings 17, as shown in Fig. 6. When the rounded hinge lugs 15 have been re-positioned in the slots 16, the wings 17 are pressed over the lugs from opposite sides, thus encircling the hinge lugs 15 and securely retaining the same and forming a bearing therefor on which the door is freely swung.

I prefer to perform the rounding operation upon the lugs 15 by some instrumentality which will simultaneously reduce the diameter of the lugs to such an extent that when the wings 17 are formed around the lugs (Fig. 7) the normal thickness of the plate will be maintained at the joint. If the lugs have been slightly lengthened in this operation, they can be readily cut to such length that they are freely accommodated in the slots 16.

While no great mechanical strength is demanded of a hinge joint for devices of this character, I have found that the present joint has substantially as much strength as that of the ordinary face plate hinge. The appearance of the plate is improved. The operations of manufacture are readily effected by machines of well known type. The necessity for additional metal elements is eliminated, and the location of the joint is such that the door may be opened to a more convenient extent than has hitherto been possible.

Various modifications in details will readily occur to those dealing with the problem, without departing from what I claim as my invention. For example, the lugs 15 may be formed as projections from the opposite sides of the door butt opening in the face plate, and the slot 16 may be formed in the door butt. In this case the swaged lugs 17 would be formed in the metal in the door butt. Obviously the same type of hinge is obtained by this reverse arrangement of the parts as in the construction above described.

I claim—

1. A hinge joint comprising a plate, a door struck therefrom, and hinge means uniting said door and plate, said hinge means comprising integral lugs on one of said members and cooperating recesses in the other of said members in which said lugs are received and journalled substantially in the plane of the plate.

2. A hinge joint comprising a plate, a door struck therefrom, and hinge means uniting said door and plate, said hinge means comprising integral lugs on one of said members and cooperating recesses in the other of said members in which said lugs are received and journalled substantially in the plane of the plate, said lugs being of substantially circular cross section.

3. A hinge joint comprising a plate, a door struck therefrom, and hinge means uniting said door and plate, said hinge means comprising integral lugs on one of said members and cooperating recesses in the other of said members in which said lugs are received and journalled substantially in the plane of the plate, together with means integral with the recessed member for detaining the lugs.

4. A hinge joint comprising an apertured plate, a door for said aperture, and self-contained interengaging hinge elements integral with said door and plate for hinging the door to the plate substantially in the plane of the latter.

In testimony whereof I have signed my name to this specification.

GILBERT W. GOODRIDGE.
